UNITED STATES PATENT OFFICE.

WILLIAM F. GAMMETER, OF FREEPORT, OHIO, ASSIGNOR OF THREE-FOURTHS
TO ROBERT STEWART, J. FRANK McMATH, AND N. MACGRAY, OF SAME
PLACE.

ACETYLENE-GAS GENERATOR.

SPECIFICATION forming part of Letters Patent No. 664,940, dated January 1, 1901.

Application filed November 4, 1899. Serial No. 735,741. (No model.)

To all whom it may concern:

Be it known that I, WILLIAM F. GAMMETER, a citizen of the United States, residing at Freeport, in the county of Harrison and State of Ohio, have invented new and useful Improvements in Acetylene-Gas Generators, of which the following is a specification.

My invention relates to improvements in acetylene-gas generators, and has for its object the providing of a number of novel features and details of construction, as will be hereinafter more fully described and claimed.

Figure 1 is a perspective view of the generator with parts of the casing cut away. Fig. 2 is a detailed perspective view of the condensing and cooling tubes and the double drip-tanks and their connections therewith. Fig. 3 is a perspective view of the forward end of the carbid-box receptacle. Figs. 4 and 5 are detailed perspective views of the carbid-boxes. Fig. 6 is a sectional view of a portion of the door-frame. Fig. 7 is a sectional view of a portion of the edge of the door. Fig. 8 is a detailed perspective view of a portion of the rod carried by the gasometer and by means of which the water-supply is controlled. Fig. 9 is a plan view of the condensing and cooling chamber through line X X, Fig. 2. Fig. 10 is a longitudinal sectional view of the machine through the center thereof. Fig. 11 is a sectional view through the line Y Y. Fig. 12 is a sectional view through the line Z Z.

In the accompanying drawings similar letters of reference refer to similar parts.

A represents the casing, which may be of any desired size, but cylindrical in form and open at top and bottom. Intermediate the top and bottom of this casing there is provided a plate B of a diameter equal to the diameter of the casing and securely engaging the sides of the casing and which, in combination with the upper portion of the casing, forms the tank for holding the gas. Below the plate B there is inserted in the casing the carbid-box receptacle C, which consists of an oblong box open at its forward end and having attached thereto a frame upon which is formed the projecting flange c, by means of which it is riveted to the casing. The

door-frame c² has formed upon its face the rib c³, and upon either side of the door-frame there are provided L-shaped projecting lugs c⁴. To this frame there is hinged upon one side the door c⁵, having upon its edge a rubber gasket c⁶. The door is adapted to be held in engagement with the frame by means of the crab c⁷, which passes around the door and engages with the lugs c⁴ on both sides of the door-frame. On the inside of the carbid-box 55 receptacle C and upon both sides thereof I provide flanges c⁸, which act not only as a support for the carbid-boxes when more than one is used, but serve the double purpose of directing the water which forms by reason of 60 the condensation produced by the contact of the hot gas upon the cold sides of the box into the receptacle attached to the lower carbid-box, hereinafter described.

I have shown two carbid-boxes D and E, 70 which may have any desired number of partitions. At one end of the carbid-box D, I provide a tube d, which communicates with the lower carbid-box E. Around the lower carbid-box E and forming the bottom thereof 75 I have provided a drip-tank e, which receives the moisture which may be condensed on the sides of the carbid-box receptacle.

On both sides of the casing I provide open lattice doors F and F', hinged or otherwise 80 detachably secured to the side of the casing, which permits of the lower portion of the casing being entered for the purpose of repairing or cleaning any of the parts of the generator contained therein. Upon one side of the 85 casing I have provided two communicating sealed tanks or drums G and H. These tanks are joined together by means of a communicating tube or pipe g, which maintains a uniform water-level therein, and for the purpose 90 of sealing said tanks and the pipes which enter the same I have provided on the side of the tank G a funnel g', which has a pipe connection g² with the tank, and for the same purpose the funnel h has a pipe connection h' 95 with the tank or drum H. The upward extension of the pipe g in the tank H above the line of the water seal or level permits of the use of an oil-float, which serves the double purpose of resisting back pressure and cleans- 100

ing the gas. In the bottom of the tank H there is provided a clean-out h^3 , made of any desired form, by means of which the sediment, all of which accumulates in this tank, 5 may readily be removed.

1 I is the gasometer, cylindrical in form and of a diameter less than the diameter of the casing and having a closed top and open bottom and carried upon a supporting-rod i, securely mounted in the center of the plate B and having a telescoping connection with the rod i by means of the casing i'. At one side of the top of the gasometer I provide the cup-chamber J, communicating with the gasometer and receiving the tubes as the gasometer descends. The cup-chamber J has a tubular extension j, which extends down into the gasometer and prevents siphonage above the line of the body of the water seal. 15

20 For the purpose of purifying and cooling the gas as the same arises from the generator I provide the deflecting communicating tubes K, as shown in Fig. 10. Arising from the generator there is a communicating pipe k, communicating with the drum or tank H. Attached to the upper part of the drum or tank H and communicating therewith I have provided the U-shaped tubes k' k², and at one side of the top of the drum or tank H and 25 extending into the same there is provided the pipe k³, which carries the gas into the gasometer. The free end of the U-shaped cooling-tube k' extends down into the drum H and is sealed. One member of the tube k² and the lower end of the tube k³ are surrounded by the partition k⁴, which serves to 30 direct the gas from k² into k³. The upper end of the tube k³ is bent outwardly until it comes in line with the cup-chamber J, thus 35 doing away with two cup-chambers. 40

The gas is conducted from the gasometer by means of the pipe g³, which has a T connection with the exit-pipe g⁴. The lower end of the pipe g³ extends down into the tank G and is sealed by the water therein. 45

50 As a safety-exit to the exterior I provide the pipe g⁵, which has an open-ended T connection with a pipe g⁶, communicating with the exterior at a point above the casing and has a telescopic engagement with the tubular extension j of the cup-chamber J. The tubular extension j has an aperture j² near the line of the water seal of the gasometer, so that if 55 for any reason the exit-pipe should become clogged or the gas be generated faster than it could be taken care of by the gasometer the gas would pass out through the opening j², thence up into and down through the tube g⁵, and thence to the exterior. 60

As an additional safeguard and in event of back pressure on the tube k³ when the carbid-receptacle door is opened, the tube g between the tanks G and H serves as a means of communicating with the exterior of the gasometer. 65

The gas being forced back down the tube k³ will break the seal by forcing the water to

rise in the tubes k', thus permitting the gas to pass out through the communicating tube g.

On the side of the casing A, and securely attached thereto there is provided a water-tank L, which has a pipe connection with the carbid-box by means of the supply-pipe l. Just below the water-tank there is provided a valve l', operated by means of the lever l², adapted to engage a slotted aperture m in the 70 sliding rod M, securely attached to the top of the gasometer and having sliding engagement with guideways upon the side of the casing. For the purpose of more readily engaging the lever l² with the aperture m I provide the projecting tongue m², which as the rod descends directs the lever into the slot. 75

For the purpose of cutting off the water-supply when it is desired to recharge the carbid-boxes I have provided lever N, securely fastened to the door and having a linked connection with the valve l', which is closed when the door is opened. 80

For the purpose of supplying water to the casing with which to seal the gasometer I provide a funnel Q on the side of the upper portion of the casing, which communicates with the interior thereof by means of the opening q. 90

In operation the carbid-boxes D and E having been filled with the carbid they are inserted in the carbid-box receptacle and the door sealed in the manner heretofore described. The water-tank L having previously been filled and a suitable amount of water introduced into the gasometer by means of the funnel Q, and the tanks G and H having been filled to the desired depth with water, the water passes from the water-tank L down through the connecting-pipe l into the upper carbid-box, when the gas begins to form and passes 100 up into the cooling-tubes K and thence up into the gasometer, which causes the gasometer to rise, carrying with it the rod M, which as it ascends causes the lever l² to lift and gradually shut off the water-supply. In case, for any 105 reason, the lever should refuse to act and the water-supply not being cut off gas should continue to be generated in a volume greater than the capacity of the gasometer the gas can be discharged through the overflow-pipe 110 communicating with the open air. After the gas has been generated and consumed, and it is again desired to recharge the carbid-boxes, the door is swung open upon its hinges, cutting off the water-supply, the upper carbid-box being removed, and then the lower carbid-box removed, and the water which may have 115 accumulated by reason of the condensation heretofore described is emptied from the drip-tank formed around its outer edge, the carbid-boxes being recharged and replaced. 120

It will be observed that by this form of multiple carbid-box the water comes in contact with only a small portion of the carbid at a time and only successive cells and successive boxes produce or form gas. 125

Having thus fully described my invention,

what I desire to claim and secure by Letters Patent is—

1. The combination in an acetylene - gas generator, of a series of two or more carbid-boxes provided with interior successively-communicating partitions, means for providing communication successively between the carbid-boxes, and a drip-tank formed upon the bottom of one of said carbid-boxes, substantially as described and for the purpose set forth.

2. The combination in an acetylene - gas generator, of a casing provided with a gasometer having a telescoping engagement therewith, a gas-generator located below the intermediate bottom of the casing, means for supplying water to the generator, means for connecting the generator and the gasometer, consisting of a series of U-shaped cooling-tubes mounted upon a drum located below the intermediate bottom of the casing, and a pipe connecting said drum and the gasometer, and a water-sealed connection between said drum and the exterior of the casing, substantially as described and for the purpose set forth.

3. The combination in an acetylene - gas generator, of a casing provided with a gasometer having a telescoping engagement therewith, a gas-generator located below the intermediate bottom of the casing, means for supplying water to the generator, means for connecting the generator and the gasometer, consisting of a series of U-shaped cooling-tubes mounted upon a drum located below the intermediate bottom of the casing, a pipe connecting said drum and the gasometer, and

a liquid-sealed connection between said pipe and the gas-generator, substantially as described and for the purpose set forth.

4. The combination in an acetylene - gas generator, of a casing provided with an open top and bottom, and having an intermediate plate inserted therein near its lower end, and securely engaging the sides thereof, a gasometer having a telescoping engagement therewith, a carbid-box receptacle mounted in the bottom of the casing, means for supplying water to the generator, a condensing and cooling coil connecting the generator and the gasometer, consisting of a series of U-shaped pipes, mounted upon a drum located below the intermediate bottom of the casing, a discharge-pipe connecting said drum and the gasometer, and a water-sealed connection between said drum and a second drum similarly located, and having a pipe connection with the exterior of the casing, substantially as described and for the purpose set forth.

5. The combination in an acetylene - gas generator, of a carbid-box receptacle provided with longitudinal projecting flanges on the inside thereof, with a carbid-box having a drip-tank formed upon the bottom thereof, substantially as described and for the purpose set forth.

In testimony whereof I have hereunto set my hand in the presence of two subscribing witnesses.

WILLIAM F. GAMMETER.
